UNITED STATES PATENT OFFICE.

BERNARD DUWEL, CHARLES DUWEL, AND FREDERICK DUWEL, OF
CINCINNATI, OHIO.

TOBACCO-DRIER.

SPECIFICATION forming part of Letters Patent No. 770,742, dated September 27, 1904.

Application filed May 22, 1902. Serial No. 108,476. (No model.)

To all whom it may concern:

Be it known that we, BERNARD DUWEL, CHARLES DUWEL, and FREDERICK DUWEL, citizens of the United States of America, and residents of Cincinnati, county of Hamilton, and State of Ohio, have invented certain new and useful Improvements in Tobacco-Driers, of which the following is a specification.

The object of our invention is a means for drying tobacco after it has been cased in which there is no probability of scorching the tobacco nor of injuring its flavor nor of allowing it to become twisted together and which is rapid and thorough in operation.

15 The means by which we attained this object is illustrated in the accompanying drawings, in which—

Figure 1 is a side elevation of a drier embodying our invention, the belt for rotating the drum being shown broken off. Fig. 2 is a longitudinal sectional view of the drum. Fig. 3 is a front elevation of the drum. Fig. 4 is detail interior elevation of the end of the conduit which conveys the currents of heated air into the front end of the drum. Fig. 5 is a transverse sectional view, upon an enlarged scale, taken upon line $\alpha\alpha$ of Fig. 1.

Referring to the parts, drum A consists of cylindrical sections a , secured to one another at their ends. The rear end of the drum is closed by a head a' , near which is a discharge-opening a^2 upon one side of the drum. The drum has three circular annular flanges a^3 , which engage rollers b^3 , journaled in brackets b^2 , mounted on I-beams B. Drum A has secured to it an external ring a^4 , which receives the actuating-belt C, which imparts a continuous rotation to the drum. The front end of the drum is closed by a cap D, which is supported upon a standard d , which is secured to the floor. Cap D is stationary, and the cylinder rotates within its flange d' . Cap D has a feed-opening d^2 , through which the tobacco is fed into the drum, which is given a slight inclination downward toward the rear, so that the tobacco is fed forward to the discharge-opening a^2 . Sections a have secured upon their interior longitudinal radial plates a^5 a^6 . Within each section we place three of

these plates at one hundred and twenty degrees apart. The plates a^5 upon one section are staggered with plates a^6 of the preceding section—that is, are at sixty degrees from them. The object of this construction is to prevent the tobacco becoming twisted or bunched, as it is inclined to do when the plates upon the adjacent sections are placed in alignment with each other. The effect of staggering the plates is to break up any twists.

Leading into the upper part of cap D is a pipe E, which upon its inner end is closed by a plate e , which has a longitudinal pipe e' leading for a short distance straight into the drum and arranged below pipe E five outwardly and downwardly directed short pipes e^2 . Through pipe E are directed currents of hot dry air. Pipe e' directs part of this current of heated air straight through the cylinder, while pipe e^2 directs part of it against the inner sides of the drum.

The tobacco, after it has been cased or flavored, is fed into drum A through opening d^2 . Drum A being surrounded by the atmosphere does not become heated up to a degree such as to scorch the tobacco which comes in contact with it. Plates a^5 keep the tobacco well separated, so that the heated air comes freely into contact therewith. We have found that tobacco so treated retains its flavor in a higher degree than that treated by processes wherein the drum is heated and that the quantity of tobacco which may be dried in a drum of a given size within a certain time is greater than in the processes aforementioned.

70 75 80 85 90 95 What we claim is—

1. In a tobacco-drier the combination of a revolving drum, an opening for feeding tobacco therein, a pipe leading into one end of the drum for conveying heated air, and a plate secured upon the inner end of the pipe carrying a main longitudinal pipe and smaller radiating-pipes for spreading and directing the heated air as it passes through the drum, substantially as shown and described.

2. In a tobacco-drier the combination of a drum made up of cylindrical sections, radiating-plates secured upon the interior of the

sections, the plates of one section being staggered with those upon the adjacent sections, an opening for feeding tobacco into the drum, a pipe leading into one end of the drum for conveying heated currents of air, and a plate secured upon the inner end of the pipe carrying a main longitudinal pipe and shorter radiating-pipes for spreading and directing the heated air through the tobacco as it passes

through the drum, substantially as shown and described.

BERNARD DUWEL.
CHARLES DUWEL.
FREDERICK DUWEL.
